UNITED STATES PATENT OFFICE.

WILLIAM BELL, OF LONDON, ENGLAND.

VENTILATING APPARATUS.

1,264,361.

Specification of Letters Patent. Patented Apr. 30, 1918.

Application filed May 12, 1917. Serial No. 168,183.

To all whom it may concern:

Be it known that I, WILLIAM BELL, a subject of the King of Great Britain, residing at 88 Norman road, Greenwich, London, 5 England, have invented a new and useful Improvement in Ventilating Apparatus, of which the following is a specification.

This invention relates to improvements in the ventilation of structures and is especially 10 applicable to the ventilation of sewers.

According to this invention the structure to be ventilated is provided with an uptake shaft and an intake shaft. The top of the uptake shaft consists of two co-axial tubes 15 and a trough surrounds the lower end of the inner tube. On the upper ends of the tubes are flanges and the spaces between the flanges are preferably divided into four parts by partitions which extend the length 20 of the inner tube. The top of the intake shaft consists of two co-axial tubes, the outer of which may be in one piece with the intake shaft and flanges on the upper ends of the tubes. Partitions divide the spaces 25 between the flanges preferably into four parts and extend between the tubes the length of the inner tube.

The accompanying drawings show the invention applied to the ventilation of a sewer. 30 Figure 1 is a section and Fig. 2 a plan partly in section.

A is a sewer leading into a depositing tank B to which is connected a shaft C having at its top two tubes D, E, the tube E being in 35 one piece with the shaft C, the lower end of the tube D being surrounded by a trough F. At the top of the tubes D, E, are flanges G, H, for directing the air into the spaces between the tubes, and the space between the

flanges and the tubes is divided into four 40 parts by partitions I. Connected to the sewer A is a shaft J having at its top two tubes K, L, the tube L being in one piece with the shaft J. At the top of the tubes K and L are flanges M, N, the space between 45 the flanges and the tubes being divided into four parts by partitions O.

By means of this apparatus air is induced into the sewer through the shaft J and is extracted from it through the shaft C. The 50 air entering the pipe J passes down into the sewer pipe A, where it commingles with the sewer gases, carrying them upward through the pipe C. The air entering the tube E is deflected upwardly through the 55 tube D, by the trough F, thereby producing a suction or draft, and causing the air to commingle with and draw the sewer gases upwardly through the pipe C, and discharging them at the top of the tube D. 60

What I claim is:—

In a structure to be ventilated, an uptake shaft connected to the structure, said uptake shaft having a top consisting of two co-axial tubes, a trough surrounding the lower end 65 of the inner tube, flanges on the upper ends of the tubes and partitions extending between the flanges and between the tubes, and an intake shaft connected to the structure, said intake shaft having a top consisting of 70 two co-axial tubes, flanges on the upper ends of the tubes and partitions extending between the flanges and between the tubes.

In testimony that I claim the foregoing as my invention I have signed my name this 75 23rd day of April, 1917.

WILLIAM BELL.
